UNITED STATES PATENT OFFICE.

CHARLES B. BARKER, OF BROOKLYN, NEW YORK.

DESIGN FOR A SPOON.

SPECIFICATION forming part of Design No. 22,639, dated July 18, 1893.

Application filed June 14, 1893. Serial No. 477,600. Term of patent 3½ years.

To all whom it may concern:

Be it known that I, CHARLES B. BARKER, a citizen of the United States, residing in Brooklyn, in the county of Kings, State of New York, have invented and produced a new and original Design for a Handle for Spoons, of which the following is a specification, reference being had to the accompanying drawing, forming a part thereof, which represents a 5 face view of a spoon embodying my design.

The design consists in the decoration of the handle, which decoration consists in the representation of a horse-shoe a forming an outer border for the end of the handle, with a four-leaf clover b inclosed within said horse-shoe. A group of flower figures c representing the forget-me-not, next follows the above, surrounded by scroll figures d. Following this is a representation of a wish-bone e. 15

What I claim is—

The design for a handle for spoons, substantially as herein shown and described.
